WORK-GUIDING ATTACHMENT FOR
SEWING MACHINES

James E. Ackerman, Devon, Conn., assignor to
The Singer Manufacturing Company, Elizabeth,
N. J., a corporation of New Jersey

Application April 8, 1938, Serial No. 200,844

9 Claims. (Cl. 112—143)

This invention relates to improvements in work-guiding attachments for use with sewing machines and more particularly in edge-folding and hemming devices, the present improvement being in the nature of an improvement in the hemming attachment disclosed in the United States patent of A. Laubscher, No. 856,166, dated June 4, 1907.

The invention has for its primary object to facilitate the production of endless edge-folds and hems in sheet materials and to this end the folder is made in separable complementary sections which are so arranged that they may be quickly and conveniently opened for the completing of the stitching operation.

Another object of the present invention is the provision of an improved supporting means for the movable section of a two-part work-guiding attachment, which supporting means is so designed that the movable section of the attachment may be shifted into either operative or retracted position readily without the necessity of releasing any latching device or securing means.

The foregoing and other objects and advantages in view, together with means whereby the same may be carried into effect, will best be understood from the following description of a preferred embodiment thereof illustrated in the accompanying drawings, in which:

Fig. 1 represents a fragmentary front elevation of a hemstitching machine and of a hemmer in its operative position as applied to the machine.

Fig. 2 represents a sectional plan view of a portion of the bed-plate of the machine and illustrates the hemmer in its operative position and, also in dotted lines, the position of the movable section of the hemmer in its opened-out or retracted position, the presser-foot of the machine being shown partly in section.

Fig. 3 represents a sectional view of the hemmer, taken substantially on the line 3—3, Fig. 2.

Fig. 4 represents a detail view in top plan of a portion of the shiftable hemmer-section carrier-arm.

Fig. 5 represents a cross-section of the hemmer adjacent the delivery end thereof.

Fig. 6 represents a fragmentary perspective view of a folded and hemstitched piece of material.

Fig. 7 represents a plan view of a hemmer which is a modification of that disclosed in the previous figures.

Fig. 8 represents a front elevation of the hemmer disclosed in Fig. 7, illustrating in full lines

the hemmer in its operative position and, in dotted lines, the position of the movable section of the hemmer in its opened-out or retracted position.

Fig. 9 represents an enlarged fragmentary view 5 taken substantially along the line 9—9, Fig. 7.

Referring to the drawings, the hemming attachment is shown as applied to a well known type of hemstitching machine, such as that forming the subject of the U. S. patent to G. M. Eames 10 et al., No. 1,721,072, dated July 16, 1929. Briefly, that portion of the hemstitching machine disclosed in Fig. 1 comprises a work-support 1 and an overhanging head 2 in which is journaled for vertical reciprocation the conventional needle-bar 3 carrying needles 4 at its lower end. The needle-bar 3 and needles 4 are actuated in the usual manner by mechanism (not shown) within the head 2.

The attachment illustrated in the first five figures of the accompanying drawings comprises a base-plate 5 pivotally supported by a fulcrum-stud 6 and bee-hive spring 7 upon the work-support 1 and held in operative position by a locating pin 8, which enters a locating aperture 9 in the 20 work-support 1. Mounted upon the base-plate 5 is a scroll-supporting plate 10 provided with an elongated aperture 11 partially covered by a washer 12 through which extend clamping screws 13 threaded preferably into two of a series of 30 apertures 14 provided in the base-plate 5. The supporting-plate 10 has fixed thereto at one end a scroll-section 15 having integrally formed therewith an apron 16 overlying the base-plate 5.

Cooperating with the fixed scroll-section 15 is 35 a movable or retractile complementary scroll-section 17 sustained by an angularly arranged carrier-arm 18 slidably mounted in a guideway 19 formed in a block 20 fastened, preferably by screws 21, upon the scroll-supporting plate 10. 40 To limit endwise movement of the carrier-arm 18, the latter is preferably formed with an elongated slot 22 adapted to be entered by a stop-pin 23 disposed in an aperture 24 provided in the block 20. A suitable cover-plate 25 is fastened, preferably 45 by screws 26, upon the block 20, thereby to prevent the carrier-arm 18 from being displaced vertically out of the guideway 19.

As will be observed from Fig. 4, the guideway 19 is so formed at 19' as to provide clearance for 50 the carrier-arm 18 when the movable scroll-section 17 is in its opened-out position. It will be seen in Fig. 2 that the free end of the carrier-arm 18 is inclined, as at 27, and rounded, as at 28, in order that the movable scroll-section 17 may 55

be shifted into retracted position. In order to maintain the movable scroll-section 17 in either operative or opened-out position, a coil-spring 29 is employed which acts between the carrier-arm 5 18 and the cover-plate 25. When the scroll-section 17 is in operative position, see Figs. 2 and 4, the coil-spring 29 urges the closed end 22' of the slot 22 in the carrier-arm 18 into contact with the stop-pin 23, while, when the scroll-section 17 is in 10 opened-out position, the coil-spring 29 because of its toggle action urges the inclined end 27 of the carrier-arm 18 into contact with one side-wall of the guideway 19, thereby holding the scroll-section 17 in retracted position. It should be understood 15 that because of the inclination of the carrier-arm 18 with respect to the direction of the normal path of feed of the material through the attachment, the work as it is fed through the machine tends to maintain the complementary scroll-sections 15 and 17 in cooperative relation. When it is desired to move the scroll-section 17 into retracted position to facilitate the completion 20 of endless edge-folds or hems, it is only necessary to withdraw the scroll-section 17 in a direction along the axis of the guideway 19 until the end 22" of the slot 22 engages the stop-pin 23, whence the scroll-section and its carrier-arm are swung in a counter-clockwise direction into the 25 position illustrated in dotted lines in Fig. 2, in which position it is maintained by the coil-spring 29. To return the scroll-section 17 to operative position, it is required only to move the scroll-section a short distance in a clockwise direction, the coil-spring 29 then functioning to complete 30 the return of the scroll-section.

Referring now to the modification disclosed in Figs. 7, 8 and 9, the attachment illustrated therein comprises a base-plate 30 upon which is supported for lateral adjustment a scroll-supporting plate 31. As in the previously described attachment, the supporting-plate 31 sustains at one end a scroll-section 32 having preferably formed therewith an apron 33. Cooperating with the fixed scroll-section 32 is an overhanging complementary movable scroll-section 34 sustained by a carrier-arm 35 endwise slidably mounted in a guideway 36 formed in a block 37 secured, preferably by screws 38, upon the supporting-plate 31. The carrier-arm 35 is slotted, as at 39, and this slot is entered by a stop-pin 40 extending upwardly from a plate 41 secured to the bottom of the supporting-plate 31. As in the previously described attachment, the stop-pin 40 functions to limit endwise movement of the carrier-arm 35 in the guideway 36.

To enable the movable scroll-section 34 to be shifted into the position illustrated in dotted lines in Fig. 8, the bottom surface of the guideway 36, in the vicinity of the inner end thereof, 60 has been cut away as indicated at 42. From Fig. 9 it will be seen that this cut-out portion provides clearance for the end of the carrier-arm 35 and permits the latter to be tilted when it is in its extreme left-hand position, thereby to enable 65 the scroll-section 34 to be moved vertically into retracted position to facilitate the completion of the endless hemming operation. As seen in Figs. 8 and 9, the plate 41 at one end is formed with an upstanding lip 43 which provides a stop 70 against which the end of the carrier-arm 35 is yieldingly maintained by the coil-spring 44 when the movable scroll-section is in retracted position.

From the above description of the accompanying drawings, it will be seen that an important

feature of the present invention is the arrangement of the carrier-arm to extend from the movable scroll-section in a direction inclined rearwardly with respect to the direction of the normal path of feed of the material through the attachment. This arrangement has the advantage that it eliminates any requirement for positively latching the movable scroll-section in hem-folding position, thereby facilitating manual shifting of the movable scroll-section. In addition, the inclination of the carrier-arm enables the work, as it is fed through the attachment, to urge the movable scroll-section into normal cooperative relationship with the fixed scroll-section. Also, the movable scroll-section is held against movement in a direction parallel with the line of seam-formation by the sidewalls of the guideway when the movable scroll-section is in operative position, which permits the operator to shift the starting end of the material to be hemmed back 20 and forth in the attachment in the direction of feed so as to properly position the material in the attachment and correctly align it with the needle.

Each of the attachments herein described is 25 adapted to produce the hem-fold illustrated in Fig. 6, the inturned raw edge E of the material M being secured by a single line of conventional hemstitching H. It is to be understood that the particular work-folding scrolls disclosed in 30 the drawings were chosen merely to illustrate the invention at hand, it being obvious that other well known types of work-guides and work-folding scrolls may be used without departing from the invention.

Having thus set forth the nature of the invention, what I claim herein is:

1. A work-guiding attachment for sewing machines comprising complementary stationary and movable work-guiding scroll-sections, and means for supporting said movable scroll-section for withdrawal from said fixed scroll-section in a direction inclined with respect to the direction of the normal path of feed of the material through the attachment.

2. A work-guiding attachment for sewing machines comprising complementary stationary and movable work-guiding scroll-sections, said movable scroll-section having an operative and a retracted position, a carrier-arm supporting said movable scroll-section, a guideway in which said carrier-arm is slidably received, said guideway being inclined with respect to the direction of the normal path of feed of the material through the attachment, and means for maintaining said movable work-guiding scroll-section in operative or retracted position.

3. A work-guiding attachment for sewing machines comprising complementary stationary and movable work-guiding scroll-sections, said movable scroll-section having an operative and a retracted position, a carrier-arm supporting said movable scroll-section, a guideway in which said carrier-arm is slidably received, said guideway being inclined with respect to the direction of the normal path of feed of the material through the attachment, means for limiting movement of said carrier-arm in said guideway, and means for maintaining said movable work-guiding scroll-section in operative or retracted position.

4. A work-guiding attachment for sewing machines comprising a supporting plate provided with a guideway inclined with respect to the direction of the normal path of feed of the material through the attachment, a stationary work-guid-

ing scroll-section carried by said plate, a complementary movable work-guiding scroll-section having an operative and a retracted position, a carrier-arm adapted to support said movable scroll-section and slidably mounted in said guideway, and means for limiting movement of said carrier-arm in said guideway.

5. A work-guiding attachment for sewing machines having complementary stationary and movable work-guiding scroll-sections, and means for supporting said movable scroll-section comprising a carrier-arm slidably mounted in a guideway formed with a clearance opening, said clearance opening positioned to receive the carrier-arm when the same is partially withdrawn from said guideway and turned about an axis to shift the movable scroll-section into a position where it is non-cooperative with the stationary scroll-section.

10. 6. A work-guiding attachment for sewing machines comprising complementary stationary and movable work-guiding scroll-sections, means including a carrier-arm for supporting said movable scroll-section, and a guideway in which 15 said carrier-arm is slidably disposed, said guideway being inclined with respect to the direction of the normal path of feed of the material through the attachment.

15. 7. A work-guiding attachment for sewing machines comprising complementary stationary and movable work-guiding scroll-sections, and a carrier-arm supporting said movable scroll-section and slidably in a guideway, said guideway being

formed in its bottom face with a clearance opening through which the carrier-arm is adapted to project when the same is partially withdrawn from said guideway and tilted vertically, thereby to separate said work-guiding scroll-sections 5 to facilitate the completion of the sewing operation.

8. A work-guiding attachment for sewing machines comprising complementary stationary and movable work-guiding scroll-sections, a carrier-arm supporting said movable scroll-section and slidably in a guideway, said guideway being formed with a clearance opening through which the carrier-arm is adapted to project when the same is partially withdrawn from said guideway and 10 tilted vertically, and a plate secured beneath said guideway and providing a stop adapted to be engaged by the end of said carrier-arm when the latter is tilted.

15. 9. A work-guiding attachment for sewing machines comprising complementary stationary and movable work-guiding scroll-sections, a carrier-arm supporting said movable scroll-section and slidably in a guideway, said guideway being formed with a clearance opening through which the carrier-arm is adapted to project when the same is partially withdrawn from said guideway and tilted vertically, a plate secured beneath said 20 guideway and providing a stop adapted to be engaged by the end of said carrier-arm when the latter is tilted, and a spring for maintaining the 25 carrier-arm in tilted position.

JAMES E. ACKERMAN.
